CLAIM

The ornamental design for a bottle, as shown and described.

DESCRIPTION

FIG. 1 is a front elevational view of a bottle, showing my new design;

FIG. 2 is a rear elevational view thereof;

FIG. 3 is a left side elevational view thereof;

FIG. 4 is a right side elevational view thereof;

FIG. 5 is a perspective view thereof; and,

FIG. 6 is a partially enlarged view thereof, taken from FIG. 5.

The broken lines portions show unclaimed subject matter only and form no part of the claimed design.

The dot-dash broken lines of FIGS. 5 and 6 are included to show a partially enlarged view only and form no part of the claimed design.

1 Claim, 6 Drawing Sheets**FIG. 1**

FIG. 2

FIG. 3

FIG. 4
